SOLVENT EXTRACTION PROCESS

Rupert C. Morris, Berkeley, and Alva V. Snider, Richmond, Calif., assignors to Shell Development Company, San Francisco, Calif., a corporation of Delaware

Application February 8, 1943, Serial No. 475,211

14 Claims. (Cl. 202—42)

This invention relates to a process for the separation of relatively high boiling organic mixtures by distilling said mixtures in the presence of a sulfolane to change the relative boiling temperatures of the components of the mixture.

It is the broad purpose of this invention to separate relatively high boiling organic mixtures of different compounds having similar vapor pressures economically, efficiently and effectively by distillation with a sulfolane to change the relative boiling temperatures of the components of the mixture. Specific purposes are, to separate high boiling organic compounds of different polarities or of different degrees of saturation; such as to purify high boiling organic compounds for use in resin, dye and other chemical industries; to separate isomers and narrow boiling mixtures of high boiling compounds difficultly separable by ordinary distillation; to purify and desulfurize lubricating oils; etc.

Generally, the process of this invention comprises the steps (A) of distilling the high boiling mixtures to be separated in the presence of a sulfolane to form at least one secondary mixture (such as an azeotropic mixture) relatively rich in one of the components of the original mixture, said secondary mixture boiling at a temperature substantially lower than the boiling temperature of said component; (B) separating said secondary mixture or azeotrope as a vapor from the remainder of the original mixture relatively rich in a different one of the components of said mixture; (C) condensing the vapor and removing the sulfolane from the condensate and usually also recovering the sulfolane removed for further contact with more of said original mixture. These steps, common to all azeotropic distillation processes, may be carried out in any suitable manner known to those skilled in the art.

Many different types of relatively high boiling mixtures of organic compounds may be separated with the aid of sulfolanes provided the sulfolane is inert toward the mixture and the presence of sulfolane in the mixture causes a greater change in the boiling temperature of one component of the mixture relative to that of the other components. For economical and complete separation it is desirable that the boiling temperatures of the resulting fractions formed be at least about 3° C. apart. If the original mixture consists of more than two components, such as a petroleum fraction, it is in general desirable that it have a boiling range of not greater than about 75° C. and preferably less than 50° C.

In order that low boiling secondary mixtures be formed between the sulfolane and a component of the original mixture, the boiling temperatures of the sulfolane and said component must be within about 75° C. of each other, and preferably closer.

High boiling mixtures which can be separated comprise petroleum or coal tar distillates, fatty acids, fatty acid esters, essential oils and other natural or synthetic organic products having boiling temperatures within the above limits and containing components having different degrees of saturation and/or polarity. Some specific examples of compounds which may be present in such mixtures and which form different boiling 10 secondary mixtures or azeotropes with sulfolanes are: paraffin, indene, various naphthalenes such as naphthalene from tetrahydronaphthalene and/or decahydronaphthalene, diphenyls, fluoranes, phenanthrene, anthracenes, fluoranthrenes, pyrene, chrysene, benzpyrenes, naphthacenes, etc.; hydrocarbon-oxygen compounds such as phenols, cresols, xylenols, cumenol, mixed alkyl phenols, duranol and naphthols, acetophenones, alkyl coumarones and diphenylene oxides; hydrocarbon-sulfur compounds such as thionaphthalenes and biphenylene sulfide; hydrocarbon-nitrogen compounds such as aniline, alkyl pyridines, quinolines, indols, carbazols, acridine; fatty acids and esters of fatty acids such as caproic, sorbic, heptoic, caprylic, capric, undecylic, lauric, sabinic, myristic, palmitic, margaric, stearic, oleic, linoleic, ricinoleic, arachatic, behenic, etc., acids; and fruit essences such as heracleum oil, banana oil and strawberry, currant, pineapple, raspberry, peach, apple, quince, etc. essences; etc.

30 The organic sulfolanes employed in the separation of such mixtures include hydrocarbon-substituted sulfolanes such as alkyl sulfolanes or derivatives thereof, wherein one or more of the hydrogen atoms in the sulfolane are replaced 35 by an organic radical which may contain a polar grouping, more specifically an organic radical containing oxygen, sulfur, nitrogen or halide atoms, provided they are vaporizable without decomposition under the conditions of the process and preferably have melting temperatures below about 150° C. and preferably below about 100° C. It is preferred to employ mostly the hydrocarbon, oxygen and sulfur polar groupings in that most nitrogen and halide derivatives as well as some esters and aldehydes are relatively heat-unstable even under reduced pressures. Further, to meet the stability requirements of this invention these sulfolanes should preferably contain not more than two olefinic 45 double bonds.

40 50

Some suitable sulfolanes are: sulfolane

and 2-sulfolene

and many of their derivatives such as hydrocarbon-substituted sulfolanes including alkyl sulfolanes, preferably containing not more than 14 carbon atoms; hydroxy sulfolanes such as 3-sulfolanol, 3-sulfolanol, 3-methyl-4-sulfolanol, 3,4-sulfolanediol, etc.; sulfolanyl ethers such as methyl-3-, propyl-3-, allyl-3-, butyl-3-, cetyl-3-, isobutyl-3-, methallyl-3-, sulfolanyl ethers and corresponding 2-sulfolanyl ethers and disulfolanyl ethers, etc.; sulfolanyl esters such as 3-sulfolanyl acetate, propionate, butyrate, caproate, etc.; sulfolanyl sulfides such as ethyl-3-, tertiary butyl-3-, isobutyl-3-, methallyl-3-, sulfolanyl sulfides; di-3-sulfolanyl sulfides, etc.; sulfolanyl sulfones such as methyl-3-, propyl-3-, amyl-3-, etc., sulfolanyl sulfones, and some of the corresponding 2-sulfolenes. The sulfolanes and 2-sulfolenes may be produced by condensing conjugated diolefins with sulfur dioxide and then submitting the resultant product to hydrogenation for sulfolanes and isomerization for 2-sulfolenes, and then further to alkylation, hydration and/or other substitution or addition reactions.

Water vapor and vapors of commonly known selective solvents may be used as auxiliary distillation aids with the sulfolane provided these solvents do not react with the particular sulfolane employed and are stable under the conditions of the process. Some suitable selective solvents which may be employed in conjunction with the sulfolanes include: various mono- and poly-hydric alcohols such as methanol, furfuryl, glycols, glycerols, etc.; various ketones such as methyl ethyl ketone, cyclopentanone, benzophenone, etc.; various aldehydes such as crotonaldehyde, furfural, etc.; ethers such as ethylene glycol, mono-alkyl ethers, chlorinated dialkyl ethers, dioxane, etc.; lower aliphatic acids, etc.; various phenols; various organic amines such as lower aliphatic primary amines, anilines, etc.; various nitriles such as lactonitrile, benzonitrile, etc.; various nitro hydrocarbons such as nitromethane, nitrobenzene, etc.; various pyridines and quinolines; various aromatic hydrocarbons such as benzene, cumene, anthracene, etc.; and the like. The amount of such additives with the sulfolane must be less than 50% by volume and preferably less than 25% by volume of the sulfolane employed.

The amount of sulfolane added to the high boiling mixture to form a secondary boiling mixture having a sufficient difference in boiling temperature from that of said high boiling mixture to make it readily separable by fractional distillation preferably should be enough to form a minimum boiling azeotrope with the component of the original mixture which it is desired to separate from the remainder. A smaller amount will result in incomplete recovery of that component. A greater amount is permissible, since the distillation may be controlled so that any excess of sulfolane appears in the bottom product of the distillation.

Fig. 1 of the accompanying drawing discloses a flow diagram of an azeotropic distillation process which may be employed in carrying out this invention, and Fig. 2 is a graph depicting the results of azeotropic versus ordinary distillation of Example I disclosed later.

Referring to Fig. 1 of the drawing, a mixture to be separated (which for convenience comprises, say, two components A and B, A forming a low boiling azeotrope with the sulfolane) is

admixed with the sulfolane and introduced through feed line 1 into the side of fractional distillation column 2 provided with reboiler 3 at its bottom. The low boiling azeotrope of A and B are vaporized and removed from the top of column 2 through vapor line 4 and condenser 5 to liquid phase separator 6. If the amount of sulfolane added to the mixture of A and B is not in excess of the amount required to form only an azeotrope with component A of said mixture, then pure component B is withdrawn through valved line 7. However, if an excess of sulfolane is added this excess must be removed and the secondary mixture of B and sulfolane is then passed through valved line 8.

In separator 6 the condensed azeotrope of A and sulfolane forms two liquid phases, an upper phase consisting mainly of component A and little sulfolane, and a lower phase consisting mainly of sulfolane and little of component A. The lower phase is withdrawn through bottom valved line 9 and recycled to column 2 to join feed line 1, thereby aiding in the separation of more of the mixture A and B. A reflux is provided to the top of column 2 from the upper liquid phase in separator 6 through valved line 10 and the remaining portion of the upper phase is withdrawn through line 11 into scrubber 12 wherein the sulfolane is washed from component A and with some suitable low boiling selective solvent for sulfolanes such as water which is introduced near the top of scrubber 12 through line 13. Pure component A is withdrawn from the scrubber 12 through top line 14 and diluted sulfolane is withdrawn through bottom line 15. This diluted sulfolane is then stripped of its water by being passed through heat exchanger 16 into concentrator 17 provided at its bottom with reboiler 18 and at its top with vapor outlet line 19, condenser 20 and accumulator 21 to provide a reflux through valved line 22 and to discharge the stripped solvent through valved line 23 to waste or through recycle valved line 24, joining line 13 for re-use in scrubber 12. The sulfolane free from solvent is withdrawn from concentrator 17 through bottom line 25 which passes through heat exchanger 16 to join the sulfolane in line 9 for recycle to column 2 and to join with mixture A and B in line 1.

If an excess of sulfolane over that required to form an azeotrope with A is added to the mixture, component B withdrawn from the bottom of distillation column 2 contains sulfolane which must be removed. The secondary mixture of sulfolane and B is then passed through valved line 8 into stripper 26 provided at its bottom with reboiler 27 and at its top with vapor outlet line 28, condenser 29 and accumulator 30 to provide a reflux through valved line 31 to stripper 26. The sulfolane stripped from component B in column 26 after being collected in accumulator 30 is passed through valved line 32 to join line 9 for recycle to column 2 to join with the mixture A and B in line 1. Pure component B is withdrawn from stripper 26 through bottom line 3.

Fresh sulfolane may be added to the system from time to time as required through valved line 34 joining line 9 and fresh solvent or water may be added to the sulfolane recovery system for component A from time to time through valved line 35, joining line 13.

The sulfolane recovery systems disclosed in Fig. 1 for the secondary mixtures withdrawn from column 2 are merely illustrative of ways in which

the sulfolane may be recovered. The sulfolane recovery system for either or both of said secondary mixtures may comprise a water scrubbing system such as shown for the recovery of sulfolane from component A, or a stripper as shown for the recovery of sulfolane from component B.

If desired, an azeotropic distillation process similar to that described in Deanesly U. S. Patent No. 2,290,636 may also be employed.

The pressures employed in the system may range from the lowest economical subatmospheric pressure, say about $\frac{1}{4}$ inch of mercury, to atmospheric pressure. Reduced pressures are particularly advantageous when the mixture to be separated is unstable at its normal boiling temperature.

The temperatures employed in distillation column 2 may range anywhere from about 100° C. up to about 350° C. Mixtures which have normal boiling temperatures above about 350° C. are usually separated at reduced pressures.

For simplicity, pumps, heat exchangers, bypasses, vents, pressure release valves, exhausters and other auxiliary equipment have not been shown in the drawing, since their application is evident at once to anyone skilled in the art.

EXAMPLE I

A mixture of equal portions by weight of amyl naphthalene and cetane was fractionated through a 20-inch ring-packed column while maintaining a reflux ratio of approximately 5:1 under an absolute pressure of about 20 mm. of mercury. This mixture had a boiling range of between about 158° C. and 164° C. During the distillation of this mixture several cuts were taken and analyzed as shown in the table below. The weight per cent of amyl naphthalene in each cut was plotted against weight per cent of the mixture distilled in Fig. 2 of the drawing whereby curve X was obtained. It can readily be seen from this curve that there was very little if any separation occurred between the amyl naphthalene and the cetane.

TABLE I

Straight fractionation of amyl naphthalene-cetane blend

Cut No.	B. R. at 20 mm.	Wt. g.	Wt. percent of charge	Refractive index	Approx. percent amyl naphthalene (from R. I.) in cut
1	158-160	14	14	1.4939	47.5
2	160	15.5	29.5	1.4926	46.5
3	160-162	15	44.5	1.4912	45.5
4	162	15.5	60	1.4906	45.5
5	162	16.5	76.5	1.4915	45.5
6	164	15	91.5	1.4968	50
Bottoms		10		1.5343	75
Amyl naphthalene	166	50		1.5730	
Paraffin hydrocarbon (cetane)	166	50		1.4959	
			Feed	1.4347	

A separate batch containing 100 g. of a mixture of equal portions by weight of amyl naphthalene and cetane was then mixed with 300 grams of 2,4-dimethyl sulfolane and fractionated at an absolute pressure of 20 mm. of mercury and under a 5:1 reflux through the same column as used in the experiment above. It was found that the cetane and 2,4-dimethyl sulfolane formed an azeotrope which, under the pressure employed, boiled at about 142° C., and that phase separation occurred upon cooling this mixture. The azeotrope consisted approximately of 25% hydrocarbon and 75% 2,4-dimethyl sulfolane.

Another azeotrope was formed with the amyl naphthalene, which azeotrope boiled at a temperature of about 151° C. to 152° C. at the same pressure. This latter azeotrope upon condensation formed only one phase and contained about 25% hydrocarbon and 75% 2,4-dimethyl sulfolane. During the distillation several cuts were taken and analyzed as seen in the table below. The 2,4-dimethyl sulfolane was removed from each cut by washing with hot water before the cut was analyzed. The results obtained from these cuts were also plotted in Fig. 2 and are represented by curve Y. From this curve it can be seen that an excellent separation between cetane and amyl naphthalene was obtained, the paraffinic fractions containing as low as 3% amyl naphthalene while the aromatic fractions analyzed as high as 98.5% pure amyl naphthalene.

Azeotropic distillation of amyl naphthalene-cetane mixture with dimethyl sulfolane

EXAMPLE II

A mixture of equal parts by weight of methyl naphthalene and an odorless kerosene (boiling range 200° C. to 255° C.) was fractionated through a 20-inch packed fractionating column at approximately 5:1 reflux ratio and under an absolute pressure of 100 mm. mercury. The mixture had a boiling range from 147° C. to 172° C. at 20 mm. of mercury pressure. During the distillation several cuts were taken and the largest percent of aromatics obtained in any cut was 73%. These cuts were analyzed as disclosed in the following table:

Straight fractionation of methyl naphthalene-kerosene blend

Cut No.	B. R. °C.	Wt. g.	Wt. percent of charge	Refractive index	Percent methyl naphthalene (from R. I.) in cut
1	147-156	8	8	1.4979	42
2	156-160	10	18	1.5150	53
3	160-162	13	31	1.5242	59
4	162-163.4	13	44	1.5324	63
5	163.4-164.4	17	61	1.5460	71
6	164	9	70	1.5508	73
7	164	9	79	1.5442	70
8	164-166	5	84	1.4789	31
9	166-172	6	90	1.4477	8
Bottoms		10	100		
Feed		100		1.5110	50

The cuts 1 through 8 thus obtained were mixed together to produce a mixture of 78 grams to which mixture was added 100 grams of unsubstituted sulfolane and 100 grams of 2,4-dimethyl sulfolane. This resulting blend was then fractionated at an absolute pressure of 100 mm. and approximately 5:1 reflux ratio, using the same column as described above. An azeotrope was obtained consisting of approximately 15% sulfolanes and 85% hydrocarbons. During the distillation several cuts were taken and analyzed as shown in the table below.

TABLE IV
Azeotropic distillation of methyl naphthalene-kerosene blend with sulfolane

Cut No.	B. R., cc.	Wt. H. C.	Wt. percent of H. C. charged	Re- frac- tive index	Percent methyl naphtha- lene (from R. I.) in cut
1	146-152	7.5	9.6	1.4595	16.5
2	152-154	6	17.6	1.4260	18.5
3	154-158	12	33	1.4737	25.5
4	158-160	9	44.5	1.4442	40
5	160-163	5	50.9	1.5237	57.8
6	163-165	10	63.7	1.5570	78
7	165	11	77.8	1.6032	99
8	165-166	10	90.5	1.6112	99
Feed:					
Hydrocarbon blend		78	100	1.5232	60
Sulfolane		100			30
Dimethyl sul- folane		100			35

The paraffinic cuts were found to contain from 16 to 23% aromatics, while the aromatic fractions analyzed substantially 100% pure methyl naphthalene.

We claim as our invention:

1. In the process for separating a vaporizable organic mixture of different components selected from the class consisting of components of different degrees of saturation and components of different degrees of polarity, comprising distilling said mixture in the presence of a sulfolane stable under the conditions of the process to form a top product comprising said sulfolane and a portion of the original mixture relatively rich in one of said components and a bottom product comprising the remainder of the original mixture rela-

tively rich in another of said components, and separating said products, said original mixture boiling within 75° C. of said sulfolane.

2. In the process for separating a vaporizable organic mixture of different components selected from the class consisting of components of different degrees of saturation and components of different degrees of polarity, comprising distilling said mixture in the presence of a sulfolane stable under the conditions of the process to form a top product comprising said sulfolane and a portion of the original mixture relatively rich in one of said components and a bottom product comprising the remainder of the original mixture relatively rich in another of said components, separating said products, and removing said sulfolane from said top product, said original mixture boiling within 75° C. of said sulfolane.

3. The process of claim 1 wherein said original mixture boils within about 50° C. of said sulfolane.

4. The process of claim 1 wherein said original mixture has a boiling range of less than about 75° C.

5. The process of claim 1 wherein said original mixture consists of hydrocarbons.

6. The process of claim 1 wherein said original mixture comprises a lubricating oil.

7. The process of claim 1 wherein said original mixture is selected from the group consisting of fatty acids and fatty acid esters.

8. The process of claim 1 said sulfolane comprising a hydrocarbon-substituted sulfolane.

9. The process of claim 1 said sulfolane comprising a sulfide.

10. The process of claim 1 said sulfolane comprising an ether.

11. The process of claim 1 said sulfolane comprising unsubstituted sulfolane.

12. The process of claim 1 said sulfolane comprising 2,4-dimethyl sulfolane.

13. The process of claim 1 wherein the temperature of distillation ranges between about 100 and about 350° C.

14. The process of claim 1 wherein the pressure for the distillation ranges between about 1 atmosphere and about $\frac{1}{4}$ inch of mercury.

RUPERT C. MORRIS.
ALVA V. SNIDER.
